ROTARY STEAM ENGINE.

No. 605,805.

Patented June 14, 1898.

UNITED STATES PATENT OFFICE.

ALFRED LEE, OF NEW WHATCOM, WASHINGTON.

ROTARY STEAM-ENGINE.

SPECIFICATION forming part of Letters Patent No. 605,805, dated June 14, 1898.

Application filed June 25, 1897. Serial No. 642,334. (No model.)

To all whom it may concern:

Be it known that I, ALFRED LEE, a citizen of the United States, residing at New Whatcom, in the county of Whatcom and State of Washington, have invented a new and useful Duplex Rotary Steam-Engine, of which the following is a specification.

My invention relates to steam-engines which have pistons rotating within annular chambers, these chambers having three fixed walls and one movable or revolving flange-wall which is secured to a central shaft, the pistons being secured to these flanges, which form one end of the annular chambers, steam being admitted by means of a slide-valve which is operated by means of a cam on the main central shaft, all for the purpose of rotating the central shaft and fly-wheel.

The objects of my invention are to improve the general construction of such engines and to produce a steam-engine that will be very effective, using steam expansively and economically, that consists of few parts, that is of simple construction and assemblage, and that will be durable and not liable to get out of order.

Other objects and advantages of the invention will appear in the following description, and the novel features thereof will be particularly pointed out in the claims.

Like letters and numerals of reference indicate like parts in all the figures of the drawings.

Figure 1 is a vertical sectional view, near one end, on the line 44, Figs. 9 and 10, showing the piston-follower G in the annular chamber 14 at the point of taking steam. It also shows a section of slide-valve E at the end of its downward stroke, with its steam-ports 9 and 10 open and in conjunction with the curved ports in the casing at points 11, 12, and 13, the lower edge of valve within the recess 61, also the exhaust-port 8, leading into chamber 7, which leads toward the exhaust into exhaust-pipe 6.

Fig. 2 is a similar view through the center of engine on the line 33, Figs. 9 and 10, showing a section of casing A, with steam-inlet 5, which leads directly into steam-chest N, Figs. 9 and 10, and the exhaust-chamber 7, which leads into exhaust-pipe 6. It also shows a section of valve E at one side of the center of valve, with

coil-spring 44 shown in elevation, also shows the valve secured to yoke 36, a section of cam K within the yoke F, the yoke being made in two parts, the bottom part having a bore fitting about a stationary piston L, which combination is for a double purpose—first, as a guide to the yoke in its upward and downward movement, and, second, to form a steam-cushion for the yoke to obviate all jar as it descends. This figure also shows the face of one of the piston-flanges H, with a part broken away showing the end of annular chamber 14, in which the piston-follower G revolves in a radius from the shaft J. The dotted lines show the piston-follower securely bolted to the flange H at 21.

Fig. 3 is a detail of one of the piston-followers G, showing it with the countersunk head-bolts, the top groove 17 to receive the packing-strip 15, and the bottom groove 18 to receive packing-strip 16, also the central hole 19 to receive the coil-spring 20, which holds the packing-strips apart and against the exterior and interior circumference walls of the annular chamber 14.

Fig. 4 is a detail of the packing-strips of the piston-follower G, showing 15 convexed on its upper side to fit the radius of annular chamber 14, also showing 16 concaved on its lower side to fit the radius of the interior circumference wall of annular chamber 14.

Fig. 5 is a detail of one of the packing-pieces which is held against the face of slide-valve E, showing one of its edges which fits the face of the valve, with a projection at an angle of forty-five degrees at 38 fitting a corresponding bevel on each outward end of valve E. The L-shaped projection 40 extends down the face of valve in a recess in the casing provided for it, and the bottom end is covered by the revolving flanges H and I. These packing-pieces are held against the face of valve E by the springs 41 (only one of which is shown, Fig. 9.)

Fig. 6 is a detail of the lower half of the cam-yoke F, showing it with its side lugs 54 to receive the bolts that secure the two halves together, Fig. 2, also the lower extension 55, which has a bore 57 to receive the stationary piston L, with four slot-openings near the upper or closed end of bore placed at equal distances about its circumference for

the purpose of admitting steam above the stationary piston L.

Fig. 7 shows a top view of cap D, showing the top of projection 42, also the bolt-holes to secure it to the main cylinder of the engine.

Fig. 8 is a vertical sectional view through the center at right angles to Figs. 1 and 2, showing the face of valve E with one of its ends broken away, showing the steam-ports 9 9 and 10 10 through the same, the top rib of valve 52, which is to stiffen and strengthen the valve, the lug 51 to receive the coil-spring 44 within its chamber 43, also the steam-chamber O, also the valve E, bolted to the top of yoke F, the two slots in the bottom edge of valve in which the flanges II and I revolve, the beveled ends 39 to fit packing-strips at 38, the slide-valve E, slightly raised, covering the inlet-ports 11 and 12 back of valve, but still covering the path of pistons in the annular chambers 14 14, as when using steam expansively. This figure also shows the fly-wheel M and the shaft J in full with the central cam K between the disks 25 and 26, the reduced end 34 within the sleeve 31, which forms one of the bearings, the end of shaft being reduced and threaded at 33 into a nut 32 with a right-hand thread, the nut being threaded into the sleeve 31 with a left-hand thread for the purpose of adjusting the sleeve on the shaft longitudinally. It also shows a section of the piston-flange II, which is a part of the casting that forms the sleeve 31. This piston-flange II is keyed to the shaft-disk 25 by means of the keys 24 24, so as to compel the shaft to rotate with it, but loosely enough to permit of the longitudinal adjustment by means of the nut 32 just mentioned. It also shows a section of the opposite piston-flange I, which is fixed on the shaft J at 35 and around the disk 26 by being shrunk on the same, and also has keys 24 24, as shown. This figure also shows a section of the bottom half of yoke F, showing the bore 57, the stationary piston L, with packing-ring 58, the threaded stem, which is threaded into lug 62, the bottom of this stem being squared to receive a wrench to turn the same at 59.

Fig. 9 is a top view of the engine with a part of cap broken away, showing the top of slide-valve E at 52, the spring-lug 51, the beveled edges of the two ends at 39 39, also showing steam-space O, the edges of flanges II and I, and between these the steam-space N N, the face of one of the packing-pieces 37 held against the face of valve E by spring 41. It also shows steam-inlet pipe 5 and exhaust-pipe 6 in the central casing A, which casing is bolted between the two flanged casings B B, these having heads C C bolted to them, as shown.

Fig. 10 is a horizontal sectional view through the center on the line 2 2, Figs. 1 and 2, which shows shaft J, section of flange I and of flange II, with sleeve 31, the two heads C C, with their interior projections forming the interior-circumference walls of the annular chambers

14 14, with section of pistons, showing the packing-strips 15 15 and 16 16, held against the walls by coil-springs 20 20, also showing the cam K, the bottom part of yoke F, and the lower part of steam-chamber N N, the upper part of this chamber being marked O, Figs. 1, 2, 8, and 9.

Having explained the purpose of the figures and enumerated the principal parts shown by each, what follows will be a more general description of the construction and operation of the engine, considering the different parts of the whole engine in their relations one to another.

The cylinder or frame of engine is made in sections. The central piece A is a separating-ring placed between the two casings B B and forms the exterior casing which surrounds the steam-chest N, in which the cam K, the cam-yoke F, and the piston-flanges II and I are placed. The ring-casing A has an open communication at the top leading from that part of the steam-chamber marked N to the upper part of steam-chamber O in cap D. Through this opening extends the valve E, secured to the top part of yoke F at 36. There is in this casing an inlet steam-pipe 5, which admits steam, also an exhaust-pipe 6 and chamber 7. The two casings B B are made with flanged ends to admit of bolts to secure them to the central casing A and the heads C C. The engine rests on the base R R, being the bottom of these casings B B. These casing-rings B B are of a smaller interior diameter than casing A to permit the lap on their ends of the piston-flanges II and I. These rings B B form the exterior-circumference walls of the annular piston-chambers 14 14. There is from these annular chambers an opening at the top, through which the slide-valve E reciprocates. From this opening are located the inlet steam-ports 11, 12, and 13. There are also located exhaust-ports 8, of same width as steam-ports, which lead into an exhaust-chamber 7, which chamber communicates with the exhaust-pipe 6. The casing-rings B B and A are so shaped at the top as to permit the cap-casing D to be bolted to them. There is a recess at the intersection of these casings with the cap-casing D to admit the L-shaped packing-strips 37 37, located at each end of slide-valve E, also room in these recesses for springs 41 41, which hold 37 37 against slide-valve E.

The heads C C, through which the shaft J turns, are shaped at 47 47 and 50 50 to extend and fit into the bore of casings B B and have flanges which are bolted to B B. These heads C C have a cup-shaped interior extension 46 46 and 48 48, which is of smaller circumference than the bore of casings B B and extends flush with the same, forming the interior-circumference wall of the annular piston-chambers 14 14. It will be observed that the heads C C and the casings B B form the three stationary walls of the annular chambers 14 14, in which the piston-followers G G

travel, and the flanges H and I, to which the piston-followers are securely bolted, form the fourth or revolving walls of the annular chambers. These flanges turn close enough to the end walls of the annular chambers to prevent the passage of steam.

The main central shaft J has at its center a cam K between two disks 25 and 26. These disks fit into corresponding recesses in pis-

ton-flanges H and I, which flanges are kept from turning on the shaft by keys 24 24. The flange I is made secure and fixed on the shaft J at 35 by being shrunk on the same. The flange H has a central sleeve extension 31, which has a central bore, through which the end 34 of shaft J passes, the shaft being reduced in this portion to allow for the thickness of shell of sleeve 31. The end 33 of shaft J is still further reduced and is threaded into a nut 32 with a right thread, this nut 32 having an exterior left thread which fits into a corresponding thread in the end of sleeve 31. As this flange H, with sleeve 31, fits loosely on shaft J, by turning nut 32 to the right the flange H is forced toward the flange I, while a left turn separates them. By this means all wear can be taken up as desired or the flanges made to revolve as close to the end walls of annular chambers 14 14 as desired, thus making and keeping the same steam-tight.

The cam K of shaft J revolves within a yoke F. This yoke has an extension 36 on its upper half which fits and is securely bolted to slide-valve E. Figs. 1 and 2 show this slide-valve at its lowest point, closing the annular chambers 14 14 behind the piston-followers G G, with the inlet steam-ports 9 9 and 10 10 of valve E open and in conjunction with ports marked 11, 12, and 13 allowing live steam to enter between piston-followers G G and valve E, forcing forward the piston-followers. As these are bolted to the flanges H and I and these keyed to the shaft J, said shaft will be revolved under live steam until the point 27 on cam K comes up against the yoke F at point 30, lifting the same and with it the slide-valve E sufficiently to cover the steam-ports 11 11 and 12 12, as shown, Fig. 8, cutting off all steam at this point, then using the confined steam expansively until it loses its expansive force and is released through exhaust-ports 8 8. As the travel of pistons is great, it will be observed that a high per cent. of the force in the steam will be utilized before the pistons make a full revolution or the point 20 of cam K comes under the point 30 of yoke F, lifting the valve E clear from the path of pistons. At this point of each revolution, it will be observed, there will be a dead-point, which is overcome by the momentum of the fly-wheel M acting on shaft J. When the pistons have passed the path of valve E, the point 28 of cam K leaves the point 30 of yoke F, allowing the valve E to close instantly the path of pistons in the annular chambers by the pressure of live steam in the chamber O acting with considerable

force on the upper ends of slide-valve E, and to avoid any shock or noise from the sudden stopping of the valve in its downward stroke 70 there is provided a stationary piston L, with a stem threaded into lug 62 and through casing A, having a jam-nut 60 on the outside of casing, the end of stem being squared at 59 to permit of being turned up or down with a 75 wrench.

The head on stationary piston L is provided with a snap-ring 58, put on in the usual manner. This head fits the bore 57 of yoke F. As the yoke with valve E ascends the openings 56 56 come above the piston L. As these are all within the chamber of live steam, steam rushes in above the piston-head, and as the valve is forced downward and with it the yoke there is live steam confined above the 85 piston-head L within the bore 57 of yoke F. This steam being confined will greatly increase the pressure within the bore and form a cushion, obviating the sudden shock of the downward stroke. By means of this screw 90 adjustment this steam-cushion can be made great or less as required.

There is provided at the top of valve E a coil-spring 44, with its upper end incased within a chamber to receive it. This spring 95 compresses when the valve rises and insures the positive action of valve in case the steam-pressure is very low and not sufficient to overcome the friction on the valve occasioned by the packing against the valve and the bottom 100 of yoke.

The chambers P P and Q Q are oil-chambers to be partly filled with lubricating-oils to lubricate the contiguous bearings.

From the foregoing description, in connection with the accompanying drawings, it will be seen that I have provided a duplex rotary steam-engine that consists of few parts, the same being durable, readily removed, and positive in their operations and that by their movements I produce an engine that can be run at high speed, that uses steam expansively to a high degree and hence economically and effectively, and one in which the possibility of leakage or loss of steam is reduced 115 to a minimum.

I do not limit my invention to the precise details of construction herein shown or described, but hold that I may vary the same to any degree and extent within the knowledge 120 of the skilled mechanic.

Having described my invention, what I claim is—

1. In a duplex rotary engine, in combination, the sectional cylinder-casings A, B B 125 and heads C C through which shaft J turns, the annular chambers 14 14 in which the piston-followers G G rotate, these piston-followers having packing-strips 15 15 and 16 16 held apart and against the exterior and interior 130 circumference walls of the annular chambers 14 14, the flange I which is fixed stationary on the shaft J by being shrunk on the same and also by being keyed to the shaft-disks 26

by means of keys 24 24, this flange having a recess to receive the disk 26 and having bolted to it one of the piston-followers G at 22, the flange II having a recess to receive the shaft-disk 25, and having bolted to it one of the piston-followers G at 21, being keyed to the shaft-disk 25 by means of keys 24 24 so that the shaft shall rotate with it, but keyed loosely enough as to be longitudinally adjustable, this flange 5 II also having a sleeve 31 which fits on shaft J so as to be movable longitudinally, this sleeve 31 having an adjusting-nut 32 threaded into its outer end with a left thread and onto the end of shaft J with a right thread, the shaft 10 J having the fixed disks 25 and 26 onto which the flanges H and I are keyed, having one part 34 reduced to receive the sleeve 31, and having its extremity still further reduced and threaded to receive the adjusting-nut 32, substantially as specified.

2. In a duplex rotary engine, in combination, the sectional cylinder-casings, the annular chambers 14 14, the piston-followers G G, the rotating flanges II and I, the key-pins marked 24, the shaft J, the cam K of the shaft J located between the two shaft-disks 25 and 26, having the projections 27 and 28, the yoke F, having an irregularly-curved opening in which the cam K rotates, having 25 a projection 30 against which the two projections 27 and 28 of the cam in its rotation impinge for the purpose of lifting the yoke and the valve and giving the valve its two unequal movements in each revolution of the piston, substantially as specified.

3. In a duplex rotary engine, in combination, the shaft J, the cam K of the shaft J located between the shaft-disks 25 and 26, having the projections 27 and 28, the yoke F having 30 an irregularly-curved opening in which the cam K rotates, having a projection 30 against which the two projections 27 and 28 of the cam in its rotation thrust for the purpose of lifting the yoke F and the valve, this 35 yoke consisting of two pieces securely bolted together so as to act as one, the lower portion having a bore 57 which fits about and reciprocates upon a stationary piston L, this bore having openings marked 56 about its 40 circumference to admit steam within the bore above the piston L for the purpose of cushioning the stroke of valve, the stationary piston L, having packing-rings of the usual character, having the screw-adjustment extension 50 45 55 59 with jam-nut 60, for the purpose of adjusting the piston vertically and regulating the amount of steam compression in the bore of yoke, the cylinder-casing A to which this stationary piston is attached, substantially as 60 specified.

4. In a duplex rotary engine, in combination, the shaft, the cam K of shaft, the yoke

F having projections 30, in which yoke the cam K having projections 27 and 28 rotates to lift the same, having a bore in its lower 65 portion to receive the piston L, the piston L having screw-adjustment extension 59 and jam-nut 60, the cylinder-casing A supporting the piston L, the slide-valve E securely bolted to yoke F so as to reciprocate with it, 70 this valve having a top rib 52, a spring-lug 51, a coil-spring 44, and having ports 9 9 connecting with steam-space O and the ports 11 11 in the casing, having ports 10 10, connecting with ports 12 12 and 13 13 in the casing, 75 having slots in its lower edge to receive the flanges H and I, having beveled edges 39 39, the packing-pieces 37 37 of valve, each having a projection 38 on one side at an angle of forty-five degrees, to which fit the beveled 80 edges of valve at 39 39, each having also an L-shaped extension 40, which extend downward and are covered by the edges of flanges H and I, having also the springs 41 41 which hold the two pieces 37 37 against the valve, 85 substantially as specified.

5. In a duplex rotary engine, in combination, the cylinder A, having an inlet steam-chamber N, the steam-chamber O in the cap-casing D, the channel in which the valve E 90 reciprocates connecting the chambers N and O, the slide-valve E securely bolted to the yoke F so as to reciprocate with it, this valve having the top rib 52, the spring-lug 51 for receiving the spring 44, and the coil-spring 95 44 for the purpose of securing the positive movement of the valve, having slots in its lower edge for the purpose of receiving the flanges H and I, having beveled edges 39 39, the packing-pieces 37 37 of valve fitting 100 against the beveled edges, this valve having also ports 9 9 communicating with the steam-chamber O and the ports 11 11 in the casing, having the ports 10 10 communicating with the ports 12 12 and 13 13 in the casing, the 105 ports 11 11 and 12 12 in the casing and the channel connecting the same, the ports 13 13 between the valve and the casing leading into the annular chambers 14 14, the sectional cylinder-casing and the rotating flanges II 110 and I forming the annular chambers 14 14, the annular chambers 14 14, having the exhaust-ports 8 8, the piston-followers G G bolted to the rotating flanges II and I and rotating within the annular chambers 14 14 for 115 the purpose of rotating the shaft, substantially as specified.

In testimony that I claim the foregoing as my own I have hereto affixed my signature in the presence of two witnesses.

ALFRED LEE.
